EX

OP D 19,199

DESIGN FOR A LOUNGE.

Design No. 19,199, dated July 9, 1889.

6029

UNITED STATES PATENT OFFICE.

ADOLPH KARPEN, OF CHICAGO, ILLINOIS.

DESIGN FOR A LOUNGE.

SPECIFICATION forming part of Design No. 19,199, dated July 9, 1889.

Application filed January 2, 1889. Serial No. 295,253. Term of patent 3½ years.

To all whom it may concern:

Be it known that I, ADOLPH KARPEN, a citizen of the United States of America, residing at Chicago, in the county of Cook and State 5 of Illinois, have invented and produced a new and original Design for a Lounge, of which the following is a specification, reference being had therein to the accompanying photographic view.

10 The nature of my design is fully represented in the accompanying drawing, to which reference is made.

A is the back of the lounge, on which a represents the front, fluted horizontally, with 15 windows b, represented by velvet covering; c, the gable, fluted vertically; d, the roof, fluted parallel with the gable edge; and e, the chimney projecting from the rear end, fluted horizontally, and shown as being supported on a

ledge fluted angularly. The top f of the back 20 toward the foot end of the lounge is gable-shaped and is vertically fluted, thus representing the roof of an adjoining building. The side g of the building, as well as the lower portion of the lounge-back, is covered 25 with velvet or other fabric.

I claim—

In a design for a lounge herein shown and described, the back consisting of the front of a house with windows b, gable c, roof d, 30 and chimney e, as set forth.

In testimony whereof I affix my signature in presence of two witnesses.

ADOLPH KARPEN.

Witnesses:

WILLIAM H. LOTZ,
OTTO LUBKERT.
